[57] CLAIM

The ornamental design for a dual rocker or similar article, substantially as shown and described.

DESCRIPTION

FIG. 1 is a front perspective view of a dual rocker or similar article showing the design.

FIG. 2 is an enlarged detailed view of the rocker back covering taken from the circle "2" on FIG. 1.

FIG. 3 is a side elevational view of the rocker.

FIG. 4 is a plan view of the rocker.

FIG. 5 is a rear elevational view of the rocker.

Fig. 4.

Fig. 5.
